FIRE ALARM

Joseph O. Proulx, Warren, R. I.

Application March 22, 1939, Serial No. 263,549

1 Claim. (Cl. 200—142)

My invention relates to fire alarms, and has among its objects and advantages the provision of an improved switch mechanism responsive to predetermined room temperatures or direct contact with flame for setting the alarm in operation.

In the accompanying drawing:

Figure 1 is a view illustrating the switch mechanism partly in section in combination with the electric circuit;

Figure 2 is a view taken from the position indicated by line 2—2 of Figure 1;

Figure 3 is a view taken from the position indicated by line 3—3 of Figure 1;

Figure 4 is a sectional view along the line 4—4 of Figure 1; and

Figure 5 is a sectional view along the line 5—5 of Figure 1.

In the embodiment selected to illustrate my invention, I make use of an open-ended metallic tube 10 which constitutes a conductor for electric current, within which tube I provide a core 12 of insulating material. Within the core 12 I embed a wire 14, one end of which is electrically connected with a screw 16 and the other end electrically connected with a screw 18. Screw 16 extends through an insulated body 20 anchored in the opening 22 in the conductor shell 10. A spring contact 24 is mounted on the screw 16 in conductive relation therewith, but is insulated from the tube 10. A nut 26 has threaded relation with the screw 16 for firmly anchoring the upper end of the spring contact 24. I provide the nut 26 with a threaded opening for the reception of a terminal screw 28 to which I connect one end of a wire 30 leading to a source of current 32.

The lower end of the spring contact 24 is provided with a socket 34 in which I press a body 36 of insulating material having such properties as to fuse under abnormal room temperatures. A contact point 38 is carried by the spring contact 24 and is normally held in spaced relation with the contact tube 10 because of the body 36. Contact 38 includes an element 40 having a threaded shank 42 threaded into a nut 44 between which and the spring contact 24 I interpose a spring strip 46. Strip 46 is slotted at 48 to slide relatively to the shank 42, so that the strip may be adjusted longitudinally of the spring contact for varying its resiliency. Shank 42 passes through an opening in the contact strip 24 but is not adjustable relatively to the strip.

To the tube 10 I attach a nut 48' through the medium of a screw 50. Between the nut 48' and the tube 10 I interpose a conducting arm 52, and

the nut is threaded for the reception of a terminal screw 56 electrically connected with a wire 58 extending to the alarm 60. A wire 62 leads from the alarm 60 back to the source of current 32. It will thus be seen that wire 58 is in conducting relation with the tube 10 through the medium of the terminal screw 56, nut 48' and the screw 50.

In the event of abnormal room temperatures, body 36 will soften to permit the contact point 38 to engage the tube 10. The circuit through the signal 60 will then be closed as follows: from battery 32 to the wire 30, terminal screw 28, nut 26, spring conductor 24, contact 38, tube 10, screw 50, nut 48', terminal screw 56, wire 58, signal 60 and back to the source of current through the medium of the wire 62.

Screw 18 is anchored in a body 64 of insulating material, which body is secured in the opening 66 in the tube 10. Upon the screw 18 I mount a metallic washer 68 which constitutes a contact element. One end of a chain 70 is secured at 72 to the tube 10 and the other end is secured to a link 74 connected with one end of a combustible link 76 having its other end connected with a link 78 attached to the hook 80 on the arm 54. To the link 74 I attach a weight 82, which weight is arranged to engage the contact washer 68 when the link 76 is impaired through being enveloped in flame. Engagement between the weight 82 and the contact washer 68 closes the circuit through the alarm 60, notwithstanding spaced relation between the contact point 38 and the tube 10 as follows: from battery 32 to wire 30, terminal screw 28, nut 26, screw 16, wire 14, screw 18, contact washer 68, weight 82, link 74, chain 70, tube 10, screw 50, nut 48', terminal screw 56, wire 58, alarm 60 and back to the current 32. It will thus be seen that I have provided a switch mechanism which effectively closes the circuit through the alarm in case of abnormal room temperature or in cases where the switch mechanism is suddenly enveloped in flame.

I provide the tube 10 with a bracket 82 through the medium of which the switch unit may be mounted to a support, which may comprise the wall 84. The bracket is fashioned for accommodating screws 86 which may be threaded into the wall.

Without further elaboration, the foregoing will so fully illustrate my invention that others may, by applying current knowledge, readily adapt the same for use under various conditions of service.

I claim:

An alarm switch comprising a body of insulating material, a conductor shell on said body, a

terminal carried by said shell but insulated therefrom, a contact carried by said shell but insulated therefrom, a conductor embedded in said body and electrically connected with said terminal and said contact, a weighted flexible conductor electrically connected with said shell, an arm anchored to said shell, and a fusible element

connected with said arm and said weighted flexible conductor for holding the latter spaced from said contact, with said flexible weighted conductor so arranged as to fall into engagement with the contact when said fusible element is destroyed. 5

JOSEPH O. PROULX.
